UNITED STATES PATENT OFFICE.

CLARENCE A. BEARDMORE, OF ANNAPOLIS, MARYLAND.

DESIGN FOR AN INDICATOR FOR AUTOMOBILES.

57,763.

Specification for Design.

Patented May 3, 1921.

Application filed November 15, 1920. Serial No. 424,307. Term of patent 14 years.

To all whom it may concern:

Be it known that I, CLARENCE A. BEARDMORE, a citizen of the United States, residing at Annapolis, in the county of Anne Arundel and State of Maryland, have invented a new, original, and ornamental Design for an Indicator for Automobiles, of which the following is a specification, reference being had to the accompanying drawing, forming part thereof.

Figure 1 is a front elevation of an indicator for automobiles showing my new design.

Fig. 2 is a rear elevation of the same.

Fig. 3 is a top plan view of the same.

I claim:

The ornamental design for an indicator for automobiles, as shown.

CLARENCE A. BEARDMORE.
